TYPEWRITER

John H. Barr, Ithaca, N. Y., assignor to Barr-Morse Corporation, Ithaca, N. Y., a corporation of New York

Application February 16, 1931, Serial No. 516,195

15 Claims. (Cl. 197—64)

This invention relates to typewriters, and particularly to the control of the travel of the carriage in letter spacing direction. Heretofore, it has been customary to provide tabulating mechanisms for typewriters, but during a tabulating operation, the movement of the carriage is not retarded and therefore its rate of travel accelerates throughout the duration of a run, with resulting increase in the momentum 10 of the carriage. The abrupt stopping of the rapidly moving carriage creates objectionable shocks, vibrations and jars.

An object of this invention is to provide an improved mechanism for releasing the carriage 15 from its escapement, and for controlling its travel in a tabulating operation, in a novel and simple manner, and with which the rate of travel of the carriage when released may be selectively controlled.

20 A further object of the invention is to provide improved tabulating and carriage release mechanisms, with which the rate of travel of the carriage, when released, may be controlled to any desired extent, with which the control 25 of the carriage will be effective before the carriage is released, and which will be exceptionally simple, compact, dependable, durable and inexpensive.

Various other objects and advantages will be 30 apparent from the following description of an embodiment of the invention, and the novel features will be particularly pointed out herein-after in connection with the appended claims.

In the accompanying drawings:

35 Fig. 1 is a plan of a portion of a typewriter having carriage release and tabulating mechanisms, constructed in accordance with this invention;

Fig. 2 is a sectional elevation of the same, 40 with the section taken approximately along the line 2—2 of Fig. 1;

Fig. 3 is a bottom plan of part of the details shown in Fig. 1;

Fig. 4 is a sectional elevation of the mechanism of Fig. 1, the section being taken approximately along the line 4—4 of Fig. 2;

Fig. 5 is a rear elevation of part of the mechanism shown in Fig. 1;

Fig. 6 is a diagrammatic perspective of part 50 of the tabulating mechanism and brake; and

Fig. 7 is a sectional elevation similar to Fig. 2, but with parts in positions occupied during a tabulating operation.

In the illustrated embodiment of the invention, the typewriter includes a frame 10 (Figs. 1

and 2) having a forwardly extending section 11. A carriage track or guide 12 is supported from frame 10 in any suitable manner, such as by posts 13. A carriage 14 is provided with a track or guide 15 which extends along opposite edges of the track or guide 12, and anti-friction balls or rollers 16 may be interposed between the tracks or guides 12 and 15. By this mounting the carriage may travel from side to side of the frame 10 in what is known in the art as letter 10 spacing travel.

A letter spacing, or step by step, control device 17, which is also commonly known as an escapement device, is suitably mounted on an auxiliary frame 18 carried by the base or frame 15 10. This escapement device includes an escapement wheel 19 which drives a pinion 20 through a ratchet clutch 21. The pinion 20 meshes with a rackbar 22 which is mounted on and travels with the carriage. The carriage is actuated in 20 letter spacing direction by the usual spring actuated flexible strap 23, (Fig. 5), this movement being regulated by the escapement device 17. The ratchet clutch 21 permits the return travel of the carriage without operation of the escapement wheel, as usual in present typewriters.

An operating member or lever 24, (Figs. 2 and 7) is pivoted by a pin 25 to an upstanding arm 26 of the escapement frame 18, and this lever 24 is provided with a laterally extending arm 30 27 which engages in an annular groove of the movable member 28 of the clutch 21, so that when the lever 24 is rocked it will shift the movable clutch member 28 into disengaged relation with pinion 20, and against the action of clutch spring 29, (Fig. 2).

The lever 24 has a free end 30 extending into a position for engagement by a cam bar 31 (Figs. 2 and 4) which is mounted on and moves with the carriage and forms part of the carriage release mechanism. One form of such carriage release mechanism is disclosed and claimed in my prior patent, 1,697,899, issued January 8, 1929 to which reference may be had for a full disclosure. The cam bar 31 is operated laterally of its length toward and from the lever 24 by a lever 32, as explained in said patent. When said lever 32 is operated, the cam bar 31 is depressed and engages and rocks the lever 24 in a direction to disengage the clutch 45 40 from the pinion 20 and release the carriage.

The carriage 14 is also provided with a depending, swinging, tabulating frame 33 (Figs. 2 and 5), on the scale bar 34 of which are mounted any desired number of tabulator 50 55

stops 35 and carriage stops 36, both of which function to limit the travel of the carriage in a letter spacing direction. The stops 35 and 36 are adjustable along the bar 34 as usual in tabulator mechanisms, and as disclosed in the prior U. S. Patent of W. E. Barnard, No. 1,677,165, issued July 17, 1928.

A rod 37 is disposed beneath the frame or plate 10, adjacent to the rear edge of the typewriter, 10 and is rotatably mounted adjacent to its ends in bearings 38 and 39 (Fig. 3). The rod 37 extends in a direction approximately parallel to the direction of letter spacing travel of the carriage. At a point adjacent to bearing 38, the 15 plate 10 is provided with an opening 40 across which the rod 37 extends, on the rod 37 has fixed thereon an arm 41 which extends through the opening 40 into a position adjacent to the path of travel of the stops 35.

20 A screw 42 (Fig. 3) in the bearing 38 limits endwise movement of the rod 37 in one direction, and a collar 43 on the rod 37, by its abutting engagement with the bearing 39, limits endwise movement of the rod 37 in the other direction.

25 The end of the rod 37 which is adjacent to the bearing 39 is bent laterally to form a crank arm 44 that extends upwardly through an opening 45 in the plate 10 and is pivotally connected to one end of a link or rod 46. The rod 46 extends forwardly of the typewriter and along the extension 11 of the frame 10 (Figs. 1 and 6), and at its forward end is pivotally connected to one arm of a bell crank lever 47 which in turn is pivoted in a bearing plate 48 of the frame.

30 The bell crank lever 47 is connected to a tabulator key 49, and the latter is guided in its movement by the lever 47 and by a spring actuated lever 50 to which the key 49 is also pivotally connected. When the key 49 is depressed, the rod 37 will be rocked angularly in a counter-clockwise direction (Figs. 2, 6 and 7). This rocking movement of the rod 37 carries the free end of the arm 41 into the path of the travel of the tabulating stops 35, as shown in Fig. 7. When the key 49 is released the spring actuated lever 50 returns the key to its normal, elevated position, and rocks the rod 37 in a direction to remove the arm 41 from the obstructing position shown in Fig. 7 and return it to the inactive position shown in Fig. 2.

35 A link 51 (Figs. 2, 6 and 7) is forked at one end to embrace arm 41, and is pivotally connected to the arm 41 by the pin 52. The other end of the link is provided with an aperture in which is rotatably supported an angular end 53 of a stirrup element 54. The other end of element 54 is also bent angularly and rotatably mounted in an aperture in the end 30 of the lever 24 which actuates the clutch 21. The link 51 therefore is 40 supported at one end for pivotal and endwise movement by the rocking of the element 54 in its connection to the lever 24. In this respect the element 54 acts something like a stirrup which swingingly supports one end of the link 51.

45 The arm 41 is normally in an oblique or inclined position, as shown in Figs. 2, 6, and 7, and therefore when it is shifted, through actuation of tabulator key 49, into the path of a tabulator stop 35, that is, from the position shown in Fig. 2 into the position shown in Fig. 7, the forked end of the link 51 will be elevated and also moved toward the escapement device. The link 51, between its ends, is provided with a brake shoe or pad 55 which is brought into engagement 50 with a surface of the carriage, such as the lower

edge of the carriage guide 15, when the link 51 is elevated through upward movement of the arm 41.

The shoe or pad 55 engages the carriage before the arm 41 is fully elevated, and hence during further movement of arm 41 the shoe or pad 55 will rock upon the carriage as a fulcrum, and the end of the link 51 to which the element 54 is connected will be depressed. The depression of that end of link 51 creates a downward pull upon the stirrup element 54, and through it rotates the lever 24 to open the clutch 21 and release the carriage from the escapement device. The carriage is then free to travel until stopped by the engagement of a tabulator stop 35 with the arm 41, and during such travel the carriage is frictionally retarded by the brake shoe or pad 55, so that its movement is not too rapid.

The bearing 39 for the rod 37 is adjustable laterally of the rod 37 to a limited extent by 20 reason of slots 56, (Fig. 3) in the bearing through which pass the screws 57 which secure the bearing to the frame 10. The tightening of the screws 57 secures the bearing 39 against displacement.

25 By shifting the bearing 39 laterally it is possible to change the inclination of arm 41, as the shaft 37 would thus be rotated slightly about its pivotal connection with rod 46. This is desirable to adjust the relation of the position of arm 41 and the time of disengaging the clutch 21, so that when the carriage is released for its free tabulating movement the arm 41 will be exactly in line with the stop 35 for proper engagement therewith.

30 In operation of the tabulator, the clutch spring 29 supplies the initial spring tension to hold the pad 55 against the carriage. When the link 51 is operated, as has been already described, to disengage the clutch 21 the action compresses 40 the clutch spring 29. The amount of compression of the spring 29 is limited by the possible motion of the clutch piece, but the key 49 may be still further depressed because of flexibility of connecting parts, and the greater this depression 45 the greater the amount of pressure which will be applied to the pad 55, and consequently the greater the frictional resistance against the pull of the carriage driving means 23, and the slower the movement of the carriage and the less the impact at stop.

35 This depression of key 49 is regulated by a stop screw 49a, Fig. 6, located in a rigid member 55 of the typewriter frame, as 11, so that when the key 49 is depressed in the operation of tabulating, its downward movement is limited and controlled by said stop screw 49a. If this screw is adjusted to shorten the downward travel of key 49, then the amount of pressure on pad 55 is lessened and the carriage will move with relatively greater speed because of less friction. If the stop screw 49a be adjusted to allow greater depression of key 49, then greater pressure takes place, with greater tension applied to pad 55, and the speed of travel of the carriage correspondingly slowed down. Wear of the friction pad may be compensated for by the adjustment of the screw 49a.

40 It will be noted that in the sequence of functional performance of the parts as described, 70 the frictional control of carriage will be applied before the clutch of the escapement mechanism can be disengaged to release carriage for its free travel, and after the carriage has reached the end of said travel, and comes to rest against the 75

tabulator stop, this frictional control is not removed until after the teeth of the clutch have again engaged. This prevents rebounding of the carriage and the possible incorrect engagement of clutch teeth.

The operation of the device would appear to be clear from the foregoing description, but will be briefly set forth. In the normal use of the typewriter, the tabulator key 49 is elevated, the 10 arm 41 is in its lower or unobstructing position, shown in Fig. 2, and the clutch between the escapement wheel and the pinion 20 is effective or closed. The carriage is given the usual step by step letter spacing movement during the 15 operation of the printing mechanism, and may be returned to a new position for the beginning of a new line.

If one desires to release the carriage for movement in letter spacing direction independently 20 of the escapement device, it is merely necessary to operate the carriage release mechanism through the lever 32 (Figs. 1 and 4). Through operation of this lever the cam bar 31 is depressed and this bar in turn rocks the lever 24 25 to open the clutch 21 between the pinion 20 and the escapement wheel 19. The carriage then travels in either direction without restriction by the escapement device. When the lever 32 is released, it is returned to its normal position by 30 its own mechanism, as set forth in my prior patent hereinbefore referred to, the spring 29 of the clutch returns the clutch to closed position, and the lever 24 is returned to its normal position.

If now one desires to tabulate, the tabulator stops 35 are adjusted to the proper positions on the scale bar 34. Thereupon when the key 49 is depressed, the arm 41 will be shifted upwardly into the path of travel of a stop 35. 40 During this movement of the arm 41, the brake shoe 55 will first be applied against the carriage to retard frictionally the travel of the carriage, and up to this time the end of the link 51 adjacent to the escapement device has swung freely by reason of its support by the stirrup element 54. As soon as the shoe 55 engages the carriage, the link 51 will be rocked upon the carriage as a fulcrum, at the shoe, the stirrup element will be pulled downwardly, and the lever 50 24 will be rocked in a direction to open the clutch and release the carriage for free travel independently of the escapement wheel.

This free travel of the carriage is retarded however by the pressure of the brake shoe 55 upon the carriage, and the carriage will travel until stopped by the engagement of a tabulator stop 35 with the free end of the arm 41. Thereupon when the key 49 is released, the parts will return to normal positions and the brake shoe will be removed from its engagement with the carriage. It will be noted that in the operation of the tabulator mechanism, the brake shoe is always applied to the carriage to control the travel of the latter, before the clutch is operated 60 to release the carriage, and is not disengaged from the carriage to release it until after the clutch has reconnected the carriage to the escapement device.

The carriage and tabulator stops may be of any desired construction and examples of such stops and of the mounting of the same on the frame 33, may be found in the U. S. Patent 1,677,165 above referred to.

It will be obvious that various changes in the 70 details and arrangement of parts, which have

been herein described and illustrated in order to explain the nature of the invention, may be made by those skilled in art within the principle and scope of the invention, as explained in the appended claims.

I claim:

1. In a typewriter, a frame, a carriage mounted on said frame for travel in letter spacing direction, an escapement device, means including a clutch connecting said carriage and escapement device for controlling travel of said carriage, tabulating mechanism operable upon said clutch to disconnect the escapement device from

said carriage and a rock shaft mounted in a pair of bearings and having a single stop arm 15 for positioning in path of travel of said carriage, one of said bearings embodying means for adjusting the shaft and stop longitudinally thereto and the other bearing adjustable laterally.

2. In a typewriter, a frame, a carriage movable on said frame in letter spacing direction, a tabulator stop mounted on said carriage for travel therewith, an arm movable into and out of the path of travel of said stop with said carriage, means for causing step by step movement of said carriage, including a clutch operable to release said carriage for free travel in letter spacing direction, means connecting said arm and clutch, for operating said clutch to release

said carriage when said arm moves into the path of travel of said stop, and means operable by said connecting means and engageable with said carriage by the movement of said arm into the path of said stop, for frictionally controlling the free travel of the carriage.

3. A typewriter comprising a frame, a carriage movable on said frame in letter spacing direction, an escapement device, means including a clutch for connecting the escapement device

40 with the carriage and controlling the travel of said carriage, a tabulator stop on said carriage movable therewith, a pivoted arm swingable into and out of the path of movement of said stop, a link pivoted at one end to said arm, a clutch 45 operating member, an element pivotally connected at one end to said clutch operating member and at its other end to the other end of said link, whereby as said arm moves into and out of the path of travel of said stop, the end of 50 the link remote from said arm will swing idly about the connection between said element and clutch member, and a brake shoe connected to said link, and engageable with said carriage when said arm moves into the path of travel 55 of said stop, whereby continued movement of said arm in the same direction will cause rocking of said link by the engagement of said brake shoe as a fulcrum and through said element operating said clutch to release said carriage from 60 the escapement device.

4. In a typewriter, a frame, a carriage movable on said frame in letter spacing direction, a step by step control device, means connecting said device to said carriage including a clutch, whereby said device normally controls the travel

65 of the carriage, step by step, and may be disconnected therefrom by said clutch, a lever operating said clutch, means carried by the said carriage and operable on said lever to release the carriage, tabulating mechanism also operable upon said lever to release the carriage and stop it after a desired position is reached, and means operable by said mechanism and controlling the

rate of travel of said carriage when said carriage is released.

5. In a typewriter, a frame, a carriage movable on said frame in letter spacing direction, a step by step control device, means connecting said device to said carriage including a clutch, whereby said device normally controls the travel of the carriage, step by step, and may be disconnected therefrom by said clutch, a lever operating said clutch, means carried by the said carriage and operable on said lever to release the carriage, tabulating mechanism also operable upon said lever to release the carriage and stop it after a desired position is reached, and a brake carried and operable by said tabulating mechanism into frictional engagement with said carriage when said lever is operated to release the said carriage.

6. In a typewriter, a frame, a carriage movable on said frame in letter spacing direction, a step by step control device, means connecting said device to said carriage for controlling the letter spacing travel of said carriage, an operating member for said clutch, carriage release mechanism carried by and traveling with the carriage and operable upon said operating member in all positions of the carriage along its travel, for releasing the carriage from said device, tabulating mechanism also operable upon said operating member to operate the same and a frictional device automatically operable upon said carriage concomitantly with the action of said tabulating mechanism for controlling the rate of travel of carriage.

7. In a typewriter, a frame, a carriage movable along said frame in letter spacing direction, a step by step control device, means including a clutch connecting said device to said carriage, whereby said carriage may be released from said device by operation of said clutch, an operating member for said clutch, an element pivoted at one end to said member, a link pivoted to the other end of the said element, a tabulator stop movable with said carriage, an arm pivoted on said frame for movement into and out of the path of travel of said stop with said carriage, the other end of said link being pivotally connected to said arm, a brake pad carried by said link and operable thereby into engagement with said carriage by the movement of said arm into the path of said stop, whereby continued movement of said arm in the same direction will press the pad against the carriage to frictionally control the rate of travel of the carriage, and will also rock the link about said pad as a fulcrum to force said operating member in a direction to release said clutch and disconnect the carriage from said device.

8. In a typewriter, a frame, a carriage movable along the frame in letter spacing direction, a letter spacing control device, means connecting said device to said carriage and including a clutch, a lever pivoted on said frame and operating said clutch, an element pivoted to said lever and depending therefrom, a link pivoted at one end to the depending end of said element, mechanism including a pivoted carriage travel limiting arm in turn pivoted to the other end of said link, the axis of oscillation of said pivoted arm being approximately parallel to the axis of the pivoted connection of said link to said element, and a brake pad carried by said link and engaging with said carriage when said mechanism is operated to limit the travel of said carriage, whereby upon operation of said

arm into carriage limiting position, said link first will rock about its connection to said element until said brake engages said carriage, and then upon the carriage as a fulcrum to pull upon said element, rock said lever and disengage the clutch.

9. In a typewriter, a frame, a carriage movable along the frame in letter spacing direction, a letter spacing control device, means connecting said device to said carriage and including a clutch, a lever pivoted on said frame and operating said clutch, an element pivoted to said lever and depending therefrom, a link pivoted at one end of the depending end of said element, mechanism including a pivoted carriage travel limiting arm in turn pivoted to the other end of said link, the axis of oscillation of said pivoted arm being approximately parallel to the axis of the pivoted connection of said link to said element, a brake pad carried by said link and engaging with said carriage when said mechanism is operated to limit the travel of said carriage, whereby upon operation of said arm into carriage limiting position, said link first will rock about its connection to said element until said brake engages said carriage, and then upon the carriage as a fulcrum to pull upon said element, rock said lever and disengage the clutch, and means carried by the carriage and operable upon said lever in all positions of the carriage for rocking said lever to open the clutch without operation of said mechanism.

10. In a typewriter, a frame, a carriage movable along said frame in letter spacing direction, a rod extending approximately parallel with the direction of travel of said carriage, a pair of bearings for said rod spaced apart along the length of said rod, an arm fixed upon said rod to extend laterally therefrom adjacent one end of the rod, the bearing adjacent to the other end of the rod being adjustable in a direction laterally of the length of said rod, said other end of the rod having a crank section, mechanism carried by said frame and connected to said crank section for rocking said rod about its longitudinal axis, a stop movable with said carriage in letter spacing direction, the free end of said arm being normally out of the path of said stop and operable into carriage limiting position when said mechanism is operated, a link connected to said arm, means mounting the other end of said link for pivoted and endwise movement, a brake operable by said link into engagement with the carriage to retard frictionally the travel of the carriage, letter spacing control mechanism connected to said carriage, and means operating automatically and concomitantly with the operation of said link, for releasing said carriage from the control of said letter spacing control mechanism when said arm is shifted into position to limit travel of the carriage.

11. In a typewriter, a frame, a carriage movable along said frame in letter spacing direction, a rod extending approximately parallel with the direction of travel of said carriage, a pair of bearings for said rod spaced apart along the length of said rod, an arm fixed upon said rod to extend laterally therefrom adjacent to one end of the rod, the bearing adjacent to the other end of the rod being adjustable in a direction laterally of the length of said rod, said other end of the rod having a crank section, mechanism carried by said frame and connected with said crank section for rocking said rod about its longitudinal axis, a stop movable with said car-

riage during letter spacing travel, the free end of said arm being normally out of the path of said stop and operable into carriage limiting position in the path of said stop when said mechanism is operated, said arm being adjustable angularly about the axis of said rod by lateral adjustment of said other bearing, and means operable concomitantly with said rod and arm for releasing said carriage for travel in letter spacing direction until said stop engages said arm.

12. In a typewriter, a frame, a carriage movable on said frame in letter spacing direction, a tabulator stop mounted on said carriage for travel therewith, an arm movable into and out of the path of travel of said stop with said carriage, means for causing step by step movement of said carriage, including a clutch operable to release said carriage for free travel in letter spacing direction, means connecting said arm and clutch, for operating said clutch to release said carriage when said arm moves into the path of travel of said stop, means operable by said connecting means and engageable with said carriage by the movement of said arm into the path of said stop, for frictionally controlling the free travel of the carriage, means including a tabulator key for operating said arm, and adjustable means for limiting the movement of said key in a direction to release the carriage, whereby the friction on said carriage during its free travel may be varied by adjustment of said limiting means.

13. In a typewriter, a frame, a carriage mounted on said frame for relative travel in letter-spacing direction, an escapement controlling the letter spacing travel of said carriage device, a tabulator stop carried by said carriage, an arm shiftable into and out of the path of travel of said stop with said carriage, tabulator key mechanism operable to shift said arm into the path of said stop, means operable by said key mechanism concurrently with the movement of said stop, for releasing said carriage from said escapement device, a brake attached to and moving with said arm and engageable with said carriage to control the rate of travel of said carriage while said arm is in the path of travel of said

stop and said carriage is released from said escapement device, and means for limiting the movement of said key mechanism for varying the pressure of said brake on said carriage during a tabulating operation.

14. In a typewriter, a frame, a carriage mounted on said frame for relative travel in letter-spacing direction, and escapement controlling the letter spacing travel of said carriage device, a tabulator stop carried by said carriage, an arm shiftable into and out of the path of travel of said stop with said carriage, tabulator key mechanism operable to shift said arm into the path of said stop, means operable by said key mechanism concurrently with the movement of said stop for releasing said carriage from said escapement device, a brake attached to and moving with said arm and engageable with said carriage to control the rate of travel of said carriage while said arm is in the path of travel of said stop and said carriage is released from said escapement device, said arm being mounted on a shaft for oscillation therewith in its movement into and out of the path of said stop, and bearings for said shaft adjustable to shift said shaft both laterally and longitudinally at said arm in order to adjust the brake and said arm with respect to the stop.

15. In a typewriter, a frame, a carriage mounted on said frame for travel in letter spacing direction, means including an escapement for controlling letter spacing travel of said carriage, key operated means for releasing said carriage from the control of said escapement, yielding means for operating the carriage in letter spacing direction when said carriage is free to move in that direction, a brake operated by said key operated means whenever the carriage is removed from the control of said escapement, said carriage having a non-yielding portion engageable by said brake, when said brake is operated by said key operated means, for frictionally controlling the travel of said carriage while said carriage is removed from the control of said escapement, and an adjustable stop limiting the movement of said key and thereby the degree of pressure exerted by said brake on said carriage.

JOHN H. BARR.
